ELECTROACOUSTIC TRANSDUCER

Hugo Benioff, La Canada, Calif., assignor, by
mesne assignments, to Submarine Signal Com-
pany, Boston, Mass., a corporation of Delaware

Application May 3, 1940, Serial No. 333,158

5 Claims. (Cl. 177—386)

1

The present invention relates to electroacoustic transducers and particularly to such transducers for underwater use for transmitting and receiving compressional waves. Still more particularly the present invention relates to electroacoustic transducers in which the active element consists of one or more piezoelectric crystals.

The various objects and features of the invention as well as the manner of construction and operation will best be understood from the following description taken in connection with the accompanying drawings in which Fig. 1 is a horizontal section through one modification of the invention; Fig. 2 is a fragmentary transverse mid-section taken along the line 2—2 of the device shown in Fig. 1; Fig. 3 is a fragmentary transverse mid-section of a modification of the arrangement shown in Fig. 2; Fig. 4 is a fragmentary horizontal section of a further modification of the invention; Fig. 5 is a transverse fragmentary section taken along the line 5—5 in Fig. 4; Fig. 6 is a transverse section taken along the line 6—6 in Fig. 4; Figs. 7 and 8 show a modification of the arrangement of Figs. 1 to 3, Fig. 7 showing the right half in plan and the left half in section along the line 7—7 in Fig. 8, and Fig. 8 showing the left half of Fig. 7 in elevation and the right half in section taken along the line 8—8 of Fig. 7; Figs. 9 and 10 show a modification of the arrangement shown in Figs. 7 and 8, Fig. 9 showing the right half in plan and the left half in section along the line 9 in Fig. 10, and Fig. 10 being an elevation of the left half of Fig. 9 with the right half in section taken along the line 10—10 in Fig. 9; Figs. 11 and 12 show a further modification of the form of the invention illustrated in Figs. 4 to 6, Fig. 11 showing the right half in plan and the left half in section along the line 11—11 in Fig. 12, and Fig. 12 showing the left half of Fig. 11 in elevation and the right half in section taken along the line 12—12 in Fig. 11; Figs. 13 and 14 show a modification of the arrangement shown in Figs. 11 and 12, Fig. 13 showing the right half in plan and the left half in section along the line 13 in Fig. 14, and Fig. 14 showing the left half of Fig. 13 in elevation and the right half in section taken along the line 14—14 in Fig. 13.

As shown in Figs. 1 and 2, my device comprises a plate 1 having a radiating surface 2. The radiating portion of the plate 1 is made relatively thick to avoid bending therein but the plate is provided with a thinner annular portion 3 in which there is a groove 4 to provide a still thinner annular portion to insure freedom of motion of the surface 2 preferably in the manner

of a piston. The edges of the plate 1 may be supported in any desired manner, for example, in the housing formed by a ring 5 and a cup-shaped housing member 6 clamped together by bolts 7, a watertight gasket 8 being interposed between the plate and the housing. The plate thus closes the open end of the housing.

In the interior of the housing upon the back of the thicker portion of the plate 1 there are mounted one or more elongated members 9. These, if more than one, are arranged parallel to each other and may be held to the plate 1 by means of the screws 10. If desired, the members 9 may be integral with the member 1. On the sides of the members 9 and integral therewith there are formed laterally extending ribs 11 which act as vibratory reeds. Upon the upper surfaces of the reeds 11 there are mounted one or more piezoelectric crystals 12 preferably of Rochelle salt. The crystals 12 must be firmly secured to the surface of the reeds in any suitable manner, for example, by cementing, for, as will presently appear, the forces generated between the crystals and the members 11 are in shear. If the members 11 are of metal as shown, they will serve as one electrode for the crystals. The second electrode 13 is secured to the top of each crystal in any suitable well-known manner. Should the members 9 and 11 be made of other than electrically conducting material, it will be necessary, of course, to provide a second electrode between the crystal and the member 11 as will be understood by those skilled in the art.

The upper electrodes 13 are shown connected by strips of foil 14 or other suitable conductors to a bus bar 15 which is secured to an insulating strip 16 by means of right-angle tabs 17 and rivets 18. The insulating strip 16 is in turn supported by insulating spacers 19 and screws 20 upon the top of the several members 9. Connected in this way all the crystals on each element 9 are connected in parallel with each other. The several groups of crystals so formed may then also be connected in parallel as shown or they may be connected in series or in series parallel, depending upon the electrical conditions existing. The elements 9, being connected together through the member 1 and the screws 10, are grounded to the case of the instrument by the leads 21 and 22. Active and ground conductors 23 and 24 may pass out of the case through the watertight stuffing tube 25.

The device may be used both to transmit and to receive compressional waves under water or other liquid medium. For transmitting, an elec-

55

emotive force is applied between the conductors 23 and 24 and therefore across two opposite faces of the crystals 12. These are cut in such a manner that upon the application of an alternating electromotive force to the electrodes, the crystals will elongate and contract in the direction of their widths, that is in the direction of the double headed arrow 36 shown in Fig. 1. The forces tending to expand the crystals are transmitted by shearing action to the reeds 11. The upper surfaces of the reeds are, therefore, elongated, causing the reeds to bend downwards. Similarly a contraction of the crystals causes the reeds 11 to bend upwards. Therefore, the application to the crystals of a sinusoidal alternating potential results in a bending vibration of the reeds 11. This is transformed into a vertical vibration of the members 9, as seen in Fig. 2, of a frequency determined by the frequency of the exciting alternating potential. This preferably is made to coincide with the natural frequency of the reeds 11. The vibration of the members 9 is transmitted to the surface 2 of the plate 1 whence it is radiated into the surrounding medium.

The oscillator so formed is highly efficient and has a very low internal damping. Moreover, by properly proportioning the masses of the vibrating reeds and the members 9 and 1, a suitable amplitude transformation can be obtained between the reeds and radiating surface 2 for efficient radiation into a liquid medium.

When the device is used for receiving signals, the action is reversed. Compressional wave vibrations in the medium vibrate the plate 1 and the members 9, which in turn produce flexural vibrations of the reeds 11. This sets up elongation and contraction of the crystals, resulting in the appearance of an alternating force across the crystal faces.

If desired, the members 9 may be cut between adjacent crystals, as, for example, along the lines 26 and 27 in Fig. 1 so that each crystal section is isolated. The several crystals may then be excited with different voltages resulting in non-uniform amplitude distribution whereby any desired beam pattern in the medium can be obtained.

Fig. 3 shows a mid-sectional view of a fragment of a modification of the arrangement just described. In this modification crystals are placed on both top and bottom of the reeds 11. The crystals on the bottom must be cut along the opposite axis from those on the top so that when all the crystals are excited in phase, the top crystals will expand while the bottom crystals contract, and vice versa. The power output of the device both as transmitter and receiver can thereby be increased considerably.

The vibrating system comprising reeds formed on half wave length members is also operable by electromagnetic means as shown and claimed in my copending application, Serial No. 333,157 filed May 3, 1940.

In the modification shown in Figs. 4 to 6 the vibrating reeds are not used, but elongated ribs 28 are formed integral with the plate 1. These ribs have a height of approximately one-quarter of a wave length to form with the thickened portion of the plate 1 a one-half wave length vibrating system. Piezoelectric crystals 29 are cemented along the sides of the members 28 for vibrating or responding to vibrations of the same. The ribs 28 preferably form one electrode for the crystals, the other electrodes 30 being connected to bus bars 31 which may be mounted, insulated by

members 32 and 33, upon the plate 1 between the ribs 28 as shown in Fig. 5. The ribs 28 may be cut transversely as at 34 and 35 in Fig. 6 between separate crystals so that the various crystals may be excited with different voltages for the production of non-uniform vibrating amplitudes at the radiating surface 2 whereby any desired beam pattern can be obtained. The specific beam pattern is controlled by the form of vibration of the radiating elements in a manner which is generally treated in the British Patent No. 279,878 by giving a large diaphragm a somewhat greater amplitude at the center than at the edges and maintaining the amplitude over the whole diaphragm in the same phase. In this manner it is possible to create a sound intensity pattern of radiation which will have a large intensity loop normal to the radiating surfaces and very small secondary effects at inclined angles to the normal.

The unit may be supported in a housing 6 closed on one side by the plate 1 which is held in position by the ring 5 and the bolts 7 as in the preceding modification. The interior of the housing is filled with air or other gas. Thus the vibrating elements 28 have one end free and the other end loaded by the mass 1 and the signaling medium, whereby any desired amplitude transformation can be obtained. This structure has particular merit in the simplicity of its construction since the elements 28 and plate 1 can easily be formed from a single block of material by simple milling operations. The action of the piezoelectric crystals in this modification is similar to that in the preceding one, that is the forces of vibration are transmitted between the crystals and the ribs 28 in shear, although there is, of course, no bending action, all the crystals being energized to expand simultaneously and to contract simultaneously.

Both of the modifications just described provide an electroacoustic transducer having a substantially plane piston-radiating surface. As is well known in the art if the dimensions of the radiating surface are made large compared with the wave length of compressional waves in the signaling medium, the device will have a beam pattern in which most of the energy transmitted and the sensitivity pattern for reception will have an energy concentration in the direction of the axis perpendicular to the radiating surface. In some cases it may be desirable to be able to radiate and receive large amounts of energy in all directions especially in all directions in a plane. For this purpose a radiating surface which is cylindrical and which vibrates radially is desirable.

Figs. 7 and 8 show a modification of my invention which provides such a cylindrical radiating surface. In these figures the radiating element 41 having a cylindrical radiating surface 42 and provided at its ends with a nodal flange 43 has mounted on its inner face a plurality of elongated vibrating elements 44 all mounted with their long dimensions parallel to the axis of the cylinder and projecting radially from the internal surface of the member 41. The elements 44 are secured to the element 41 by means of screws 45 which are sunk into the outer face of the element 41, the resulting holes being made watertight by the plugs 46. The members 44 are similar to the members 9 in the modifications previously described with reference to Figs. 1 to 3. The members 44 have formed along their sides near their inner ends vibratory reeds 47. Upon the surfaces of the reeds 47 there are mounted one or more piezoelectric crystals 48.

preferably of Rochelle salt. The crystals 48 are mounted on the reed, as previously described, with their vibrational axes parallel to the surface of the reeds so that the transfer of vibrations between the crystals and the reeds takes place with the aid of shearing forces. As in the previous modification the reeds themselves may serve as one electrode for the crystals while the second electrode may be secured to the top of the crystal and connected to bus bars 49 mounted on the members 44. The several sets of crystals may be connected in any desired series and/or parallel arrangements; for example, for parallel connection the several bus bars 49 may be connected to a ring 55.

The two ends of the cylindrical structure may be closed by cover plates 50 and 51 which may be held by means of screws 54 against flanges 52 and 53 formed at the ends of the radiating member 41. The ring 55 may then be supported on the cover 51 and leads therefrom may be taken out through a watertight gland 56. If desired, the outer radiating surface of the element 41 may be cut axially as at 57 to reduce the radial stiffness of the member 41. Moreover the elements 44 may be sectioned diametrically into a plurality of elements, corresponding circumferential cuts being made on the outer surface of the element 41 as shown at 58. The operation of the device is substantially the same as that described with reference to Figs. 1 to 3.

For transmitting, an electromotive force applied across opposite faces of the crystals causes the same to elongate and contract in directions substantially perpendicular to the radial axes of the members 44 of which the reeds 47 form a part, for example, as indicated for one element 51 by the arrows 59. The forces tending to expand the crystals are transmitted by shearing action to the reeds 47 resulting in a flexural vibration of the reeds. This is transformed to a radial vibration of the members 44 and radiating member 41. The frequency of vibration is determined by the frequency of the exciting alternating potential which is preferably made to coincide with the natural frequency of flexural vibration of the reeds 47. Moreover the elements 44 together with the respective portions of the radiating member 41 which effectively vibrate therewith are preferably adjusted in length and weight so that they form a one-half wave length vibrational system in the radial direction at the natural frequency of vibration of the reeds 41. Compressional waves are thereby radiated from the entire external surface of the cylinder in all directions. If the height of the cylinder be made large compared with the wave length of compressional waves in the signaling medium at the signaling frequency, the radiation will be concentrated in a plane perpendicular to the axis of the unit.

The further modification of my invention which is shown in Figs. 9 and 10 is the reverse of that shown in Figs. 7 and 8 in that the radiation of compressional wave energy is directed toward the central axis of the unit where it may be applied to the treatment of liquids or other substances. Here the internal cylinder 61 having a radiating surface 62 has mounted on its external surface a plurality of vibrating elements 64 by means of the screws 65 which may be made watertight by the lead washers 70. As in the preceding modification, the elements 64 are provided with flexurally vibratable reeds 67 on which are mounted piezoelectric crystals 68, each having

one electrode formed by one of the members 64 and its other electrode connected to one of the bus bars 69. The operation of this device is substantially the same as that just described with reference to Figs. 7 and 8 except that the radial vibrations of the radiating surface 62 are directed toward the axis of the cylinder. For the treatment of liquids with compressional waves the end of the cylinder may be closed by means of cover plates 71 and 72 secured by screws 73 to flanges 74 and 75 formed at the ends of the radiating element 61 just beyond the nodal supporting webs 63 through apertures at the center of plates 71 and 72. A pipe 76 may be provided for conducting liquids to be treated along the axis of the cylinder. The interior of the device surrounding the pipe 76 may be completely filled with oil or other compressional wave-conducting liquid by means of the filling plug 77.

Figs. 11 and 12 show another modification of my invention providing a cylindrical radiating vibrating surface capable of transmitting compressional waves outwardly in substantially all directions and of receiving from substantially all directions. The radiating surface 82 of the radiating member 81 is operated by elongated rib-like members 88 which are similar to the members 28 in the modifications shown in Figs. 4 to 6. The members 88, however, are elongated in the axial direction and extend radially from the member 81 to form therewith a plurality of one-half wave length vibrating elements. These have secured to their sides a plurality of piezoelectric crystals 89 one of whose electrodes is formed by the members 88 and the other being connected to bus bars 83 which may be mounted on the member 81 between the elements 88. For parallel connection of the crystals the bus bars 83 may all be connected to a ring 84 positioned at one end of the structure. The radiating surface of the element 81 may be cut axially as at 85 to reduce the stiffness of this member to radial vibration. Further, the members 88 may be sectioned diametrically as indicated, for example, at 86 in Fig. 12. Corresponding circumferential cuts may also be made in the radiating surface in the element 81 as indicated at 87. The interior of the unit may be made watertight by cover plates 90 and 91 secured to flanges on the member 81 as shown. The operation of this modification is substantially the same as that described with reference to Figs. 4 to 6. The vibrational axes of the crystals are oriented to produce expansion and contraction of the crystals in the direction parallel to the sides of the members 88 upon which they are mounted as indicated, for example, by the arrow 92, in Fig. 11 and the arrow 93 in Fig. 12. The vibration of the crystals is transmitted by shearing forces to the members 88 causing them and the member 81 to vibrate radially. In receiving compressional waves the action is, of course, reversed, the radial vibration of the member 81 and the members 88 being transferred to the crystals which produce corresponding electromotive forces.

The modification of my invention shown in Figs. 13 and 14 is similar to that shown in Figs. 11 and 14 with the exception that the radiation is directed inward toward the axis of the cylinder. The cylindrical member 101 having radiating surface 102 has mounted on its external surface a plurality of rib-like members 108, preferably forming with the radiating member 101 a plurality of one-half wave length radially vibratory elements. On the sides of members 108

there are mounted a plurality of piezoelectric crystals 109 which serve to excite the members 108 and member 101 into radial vibrations. The members 108 form one electrode for the crystals, the other electrodes being connected to bus bars 103 mounted on the member 101 between the members 108. For parallel operation of the crystals the several bus bars may conveniently be connected to a collector ring 104 mounted on a flange 105 formed on the member 101. The interior of the structure may be closed by cover plates 106 and 107 fastened to the flanges 105 and 110 formed on the radiating member. A liquid-conducting pipe 111 may be passed through central apertures in the cover plates 106 and 107, the joints being made liquid tight with suitable packing material. The interior of the unit may be filled with oil or other compressional wave-conducting liquid through the filling plug 112. The operation of this modification is substantially the same as that described with reference to Figs. 11 and 12 except that the radial vibrations of the radiating member are directed inwards toward the axis of the cylinder whereby liquids conducted through the pipe 111 can be subjected to intense compressional wave vibrations.

Having now described my invention, I claim:

1. In an electroacoustic device, in combination, a piezoelectric operating means comprising piezoelectric crystal elements, means mounting said crystal elements to operate the same by a shear movement including a longitudinally vibrating element having a free end with said crystal-mounting means projecting substantially at right angles therefrom and vibrating transversely to its length near the free end, and a radiating member on which said longitudinally vibrating element is mounted substantially normally thereto.

2. In an electroacoustic device, in combination, a piezoelectric operating means comprising piezoelectric crystal elements, mounting means having a high modulus of elasticity and means cementing said crystal elements to the surface of said mounting means, said crystal elements having their electrodes in planes substantially parallel to the mounting surface of said mounting means whereby said crystals may be operated by a shear movement of said mounting means, a longitudinally vibrating element having a free end from the vicinity of which said mounting means projects laterally, and a radiating member on which said crystal-vibrating element is mounted substantially normally thereto.

3. In an electroacoustic device, in combination, a vibratory mounting unit comprising a longitudinally vibrating element having a free end, a mounting reed projecting laterally from the longitudinally vibrating element near its free end, said reed having a flat surface parallel to

its length dimension, piezoelectric crystal elements, means cementing said piezoelectric crystal elements on the mounting surface of said reeds, said piezoelectric crystal elements having electrodes extending parallelly to said mounting surfaces, and a radiating member on which said longitudinally vibrating element is mounted substantially normally thereto.

4. In an electroacoustic device, in combination, a vibratory mounting unit comprising a longitudinally vibrating element having a free end, a mounting reed projecting laterally from the longitudinally vibrating element near its free end, said reed having a flat surface parallel to its length dimension, piezoelectric crystal elements, means cementing said piezoelectric crystal elements on the mounting surface of said reeds, said piezoelectric crystal elements having electrodes extending parallelly to said mounting surfaces, and a radiating member on which said longitudinally vibrating element is mounted substantially normally thereto, said longitudinally vibrating element being tuned for the frequency it is desired to have the electroacoustic device operate.

5. In an electroacoustic device, in combination, a vibratory mounting unit comprising a longitudinally vibrating element having a free end, a mounting reed projecting laterally from the longitudinally vibrating element near its free end, said reed having a flat surface parallel to its length dimension, piezoelectric crystal elements, means cementing said piezoelectric crystal elements on the mounting surface of said reeds, said piezoelectric crystal elements having electrodes extending parallelly to said mounting surfaces, and a radiating member on which said longitudinally vibrating element is mounted substantially normally thereto, said vibrating reed and said longitudinally vibrating element being tuned substantially for the desired frequency at which said electroacoustic device is to operate.
